Des. 235,476
Patented June 17, 1975

235,476

ARTICULATED CONVEYOR UNIT

Patrick O'Neill and Patrick Joseph Douglas, Dungannon,
Northern Ireland, assignors to Powerscreen Interna-
tional Limited

Filed Mar. 14, 1973, Ser. No. 341,256

Claims priority, application Great Britain Aug. 26, 1972

Term of patent 14 years

Int. Cl. D12—05

U.S. Cl. D55—1 C

FIG. 3.FIG. 1 is a side elevation of an articulated conveyor unit showing our new design;

FIG. 2 is a plan view;

FIG. 3 is an end view in the direction of the arrow 3 of FIG. 1.

We claim:

The ornamental design for an articulated conveyor unit, substantially as shown and described.
